DISPLAY BOX

Edmond Opler, Chicago, Ill., assignor to Cook Chocolate Company, Chicago, Ill., a corporation of Illinois

Application January 8, 1948, Serial No. 143,601

Term of patent 7 years

(Cl. D58—12.6)

To all whom it may concern:

Be it known that I, Edmond Opler, a citizen of the United States and resident of Chicago, in the county of Cook and State of Illinois, have invented a new, original, and ornamental Design for a Display Box, of which the following is a specification, reference being had to the accompanying drawing, forming a part thereof.

Fig. 1 is a perspective view of a display box, showing my new design.

Fig. 2 is a top plan view thereof.

I claim:

The ornamental design for a display box, substantially as shown.

EDMOND OPLER.
